REFRIGERATING SYSTEM

Original Filed April 16, 1929

Fig. 1.

UNITED STATES PATENT OFFICE

1,985,065

REFRIGERATING SYSTEM

Christian Steenstrup, Schenectady, N. Y., assignor to General Electric Company, a corporation of New York

Original application April 16, 1929, Serial No. 355,551. Divided and this application August 3, 1931, Serial No. 554,623

13 Claims. (Cl. 62—115)

My invention relates generally to refrigerating systems.

An object of my invention is to utilize the walls of the housing or cabinet of my improved system for cooling the condenser thereof.

Further objects and advantages of my invention will become apparent as the following description proceeds, and the features of novelty which characterize my invention will be pointed out with particularity in the claims annexed to and forming a part of this specification.

In the drawing, Fig. 1 is a vertical sectional view of a water cooler embodying the novel features of my improved refrigerating system; Fig. 2 is a plan view of the lower portion of the housing of the water cooler, and Fig. 3 is a fragmentary vertical section approximately on the line 3—3 of Fig. 2.

Although my improved refrigerating system is applicable to many other forms of devices, for convenience in illustration, I have shown the same in the drawing in connection with a water cooler stand in which water is supplied to the cooling unit of the system from an inverted bottle supported over the same. This water cooler stand includes a housing or cabinet 10 in the upper portion 10' of which an inverted bottle of water 11 is supported with the mouth thereof immersed in the cooling unit 12 of the refrigerating system so as to maintain the water level therein approximately as indicated at 13. The cooling unit is provided with an evaporator chamber 14 for cooling the water in the unit and cold water is withdrawn therefrom at a push button 15 for filling a glass 16, or other vessel, which is supported in a depressed, perforated top 17 of a waste water receptacle 18 which is removably supported on the housing 10 at 19.

Any suitable refrigerating apparatus may be used to produce the desired refrigerating effect in the evaporator chamber 14, but I prefer to employ a construction similar to that described and claimed in my Patent No. 1,864,768, granted June 28, 1932, assigned to the same assignee as the present application. This apparatus comprises a closed casing 20 having a motor 21 and a compressor 22 discharging into the casing forming a unitary structure and mounted on springs 23 to make the machine quiet in operation. Cooling fins 24 are secured to the outside of the casing 20 and serve to support a condenser pipe coil 25, one end of which communicates with the casing at 26, and the other end of which communicates with a float chamber 27 from which liquid refrigerant is supplied to the evaporator

chamber 14 through the conduit 28 connected thereto at 29. During the operation of the apparatus, the heat from the casing 20 and the condenser pipe coil 25, will, if the circulation of air about them is not obstructed, induce sufficient flow of air by natural draft to cool the casing 20 and the condenser pipe coil 25. The induced draft of air flows upwardly between the fins and between the condenser and the casing, at the same time drawing air into the space between them through the turns of condenser pipe.

In accordance with my present invention, I provide openings in the housing 10, and arrange the casing 20 and the condenser 25 in such relation to these openings as to induce sufficient flow of air through the housing by natural draft to cool the casing and condenser. In the construction shown, I do this by making the lower end of the housing 10 open, and providing horizontal louvers 30 in the rear wall thereof, a lower group of which direct air into the housing 10, and the remainder of which direct air outwardly therefrom. The circulation of air through the housing is further facilitated by vertically arranged louvers 31 in the side walls of the housing. The casing 20 and condenser 25 are arranged so that air can flow freely into the lower end of the space between the casing and the condenser from the bottom of the housing, and from the lower group of louvers 30 in the rear wall of the housing 10. The air flowing between the condenser pipe coil 25 and the casing 20 which flows by natural draft, cools them and is then discharged from the housing through the upper group of louvers 30 and the louvers 31 in the side wall thereof.

In order to utilize the surfaces of the housing or cabinet 10 for cooling the condenser of the refrigerating system, I extend a pipe coil 32, which is connected between the lower end of the condenser 25 and the float chamber 27 and forms part of the condenser of the refrigerating system, about the inner walls of the housing 10 and secure the same in good thermal contact with these walls throughout a considerable portion of its length by clamps 33 attached to the walls, or by any other suitable means. In this way heat is conducted from the pipe coil 32 to the walls of the housing, which cools the coil.

It is desirable to prevent transmission of vibration or torque pulsations from the casing 20, containing the motor and compressor, to the housing 10, as such movement is very noticeable due to the ripples set up on the surface of the water in the glass bottle 11, and is also very objectionable, in many instances, as for example when the wa-

ter cooler is placed in an office. I, therefore, resiliently support the casing 20 enclosing the motor 21 and compressor 22 in the lower portion of the housing 10 on two flexible members 34 which are preferably substantially parallel to the axis of rotation of the compressor. These flexible members, or cables, are secured at the ends thereof to a rigid frame 35 by threaded couplings 36 and 37 to which the members 34 are secured by a leaded joint, and the frame is secured in the housing 10 by bolts 38. The casing 20 with the cooling fins and condenser thereon may be attached to the flexible members 34 intermediate the ends thereof in any suitable manner, but in the present instance I provide a metal strip 39 having a plurality of ears 40 bent around the cables so as to compress the same and thereby form a secure connection therewith. The strips 39 are welded to the casing 20 so that the unitary structure including the casing 20, cooling fins and condenser pipe coil 25 is resiliently supported in the lower part of the housing 10.

The compressor 22 withdraws vaporized refrigerant from the evaporator chamber 14 through a pipe 41 which communicates at one end with the upper end of the evaporator chamber at 42, and with the intake connection of the compressor indicated at 43 in the closed casing 20, the pipe 41 being formed with a coil 44 secured at one end to the frame 35 at 45, so as to permit free movement of the casing 20 on its resilient support. The connection between the condenser pipe coil 25 and the extension 32 of the condenser includes a pipe coil 32' which also permits free movement of the casing 20 on its resilient support.

I provide a simple water cooling unit which can be readily and cheaply produced. This construction is described and claimed in my application for Letters Patent Serial No. 355,551, filed April 16, 1929, and assigned to the same assignee as the present application, which is a division thereof. The water cooling unit includes receptacles 46 and 47, fitting one within the other and spaced apart to form the evaporator chamber 14. The inner receptacle 46 is secured to the bottom of the outer receptacle 47 and an outlet opening 48 is formed therein to receive the connection 49 through which water is withdrawn from the water cooler at the faucet 15. The upturned mouth of the inner receptacle 46 is expanded to form a seat 49 for a rubber, or other resilient ring, 50, on which an inverted bottle or other suitable water container is supported with the mouth thereof immersed in the water cooling unit so as to maintain the level therein about as indicated at 13. In this construction the water is cooled in flowing over the surface of the cooling unit in an attenuated stream by a circuitous, or roundabout, path from the cup 51 through the opening 52 therein to the faucet 15 so as to most effectively utilize the cooling surfaces of the unit. In this way surfaces of the water cooling unit are made readily accessible for cleaning.

In the operation of the water cooler which I have described vaporized refrigerant is withdrawn from the evaporator chamber 14 by the compressor 22 through the suction pipe 41 and coil 44, it is then discharged into the casing 20 from whence it flows to the condenser 25 and the extension thereof 32. The condensed liquid refrigerant then flows to the float chamber 27 from which it is supplied to the evaporator chamber 14 through the pipe 28 and connection 29. The motor 21 which drives the compressor 22 is intermittently operated to maintain the desired

temperature in the cooling unit by the control device 53 having a thermo-responsive device 54 extending into contact with the outer wall of the evaporator chamber 14.

When water is withdrawn from the cooling unit at the faucet 15 it flows from the inside of the cup 51 through the opening 52 and then flows in an attenuated stream about the helical corrugation between the cup and the inner wall of the cooling unit to the space in the cooling unit below the cup from which it flows to the faucet 15 through the outlet 49. In this way the cooling unit is utilized most effectively to cool the water withdrawn therefrom as it must flow in a thin or attenuated stream by a circuitous path over the surfaces of the cooling unit. Upon the water level in the cup 51 being lowered below the mouth of the inverted bottle 11 air is admitted thereto and water flows into the cup until the reduction in pressure above the water level in the bottle is equal to the head of water between the level of the water in the bottle and the cup.

Although I have shown my improved system in connection with a bottle water cooler it is apparent that many of the features thereof can be used for other purposes. I do not, therefore, desire my invention to be limited to the particular arrangement shown and described and I intend in the appended claims to cover all modifications which do not depart from the spirit and scope of my invention.

What I claim as new and desire to secure by Letters Patent of the United States, is,—

1. A refrigerating system including a cabinet, a compressor arranged in said cabinet and having a condenser coil arranged about said compressor and spaced therefrom, and another condenser coil in heat conducting relation with the wall of said cabinet so as to provide for the conduction of heat from said condenser to the wall of said cabinet for cooling said condenser.

2. A refrigerating system including a cabinet, a compressor, a casing enclosing said compressor, said compressor and casing being arranged in said cabinet, an air cooled condenser arranged about said casing and having a plurality of convolutions arranged between said casing and the wall of said cabinet and in contact with the wall of said cabinet, so as to provide for conduction of heat from said condenser coil to the wall of said cabinet for cooling said condenser coil.

3. A refrigerating system including a cabinet, a closed casing in said cabinet having a compressor therein, said casing having heat radiating fins thereon and a condenser arranged in said cabinet and carried by said fins, said condenser having an extended portion in contact for a considerable portion of its length with the inside of the wall of said cabinet so as to provide for conduction of heat from said condenser to the wall of said cabinet for cooling said condenser.

4. A refrigerating system including a cabinet, a closed casing in said cabinet having a compressor therein, said casing having heat radiating fins thereon and a condenser coil in said cabinet and carried by said fins, said condenser coil also having a plurality of convolutions about said casing and in contact for a considerable portion of its length with the inside of the wall of said cabinet so as to provide for conduction of heat from said condenser to the wall of said cabinet for cooling said condenser.

5. A refrigerating system including a cabinet having a refrigerated compartment and another compartment, an evaporator in said refrigerated

compartment, and means arranged in said other compartment and including a condenser for supplying refrigerant to said evaporator, said condenser having an extended portion in heat conducting relation with the wall of said cabinet for utilizing the wall of said cabinet to dissipate heat from said condenser.

6. A refrigerating system including a cabinet having a refrigerated compartment and another compartment, an evaporator in said refrigerated compartment, and means arranged in said other compartment and including a condenser for supplying refrigerant to said evaporator, said condenser being in the form of a coil and having a plurality of convolutions in contact with the wall of said cabinet for utilizing the wall of said cabinet to dissipate heat from said condenser.

7. A refrigerating system including a cabinet having a refrigerated compartment and another compartment, an evaporator in said refrigerated compartment, and means arranged in said other compartment for supplying refrigerant to said evaporator, said means including a conduit in heat conducting relation with an extended surface of the wall of said cabinet for dissipating heat from said means.

8. A refrigerating system including a cabinet, means arranged in said cabinet and including a condenser for supplying refrigerant, said condenser having an extended portion in heat conducting relation with the wall of said cabinet for utilizing the wall of said cabinet to dissipate heat from said condenser.

9. A refrigerating system including a cabinet, means in said cabinet for supplying refrigerant, said means including a conduit in heat conducting relation with an extended surface of the wall

of said cabinet for utilizing the wall of said cabinet to dissipate heat from said means.

10. A refrigerating system including a cabinet, means in said cabinet for supplying refrigerant, said means including a conduit having a plurality of convolutions in heat conducting relation with an extended surface of the wall of said cabinet for utilizing the wall of said cabinet to dissipate heat from said means. 5

11. A refrigerating system including a cabinet having a refrigerated compartment, an evaporator in said refrigerated compartment, and means including a condenser for supplying refrigerant to said evaporator, said condenser having a heat-dissipating portion in heat-conducting relation with the wall of said cabinet for utilizing the wall of said cabinet to dissipate heat from said condenser. 10 15

12. A refrigerating system including a cabinet having a refrigerated compartment, an evaporator in said refrigerated compartment, and means including a condenser for supplying refrigerant to said evaporator, said condenser having a heat-dissipating portion in the form of a coil and including a plurality of convolutions of 20 25 said coil in contact with the wall of said cabinet for utilizing the wall of said cabinet to dissipate heat from said condenser.

13. A refrigerating system including a cabinet having a refrigerated compartment, an evaporator in said refrigerated compartment, and means for supplying refrigerant to said evaporator, said means including a conduit in heat-conducting relation with an extended surface of the wall of said cabinet for dissipating heat from 30 35 said means.

CHRISTIAN STEENSTRUP.
